UNITED STATES PATENT OFFICE

HOWARD E. CHRISFIELD, OF JOHNSON CITY, NEW YORK, ASSIGNOR TO ENDICOTT JOHNSON CORPORATION, OF ENDICOTT, NEW YORK, A CORPORATION OF NEW YORK

DESIGN FOR A SHOE SOLE

Application filed October 16, 1929. Serial No. 33,054. Term of patent 7 years.

To all whom it may concern:

Be it known that I, HOWARD E. CHRISFIELD, a citizen of the United States, residing at Johnson City, in the county of Broome and State of New York, have invented a new, original, and ornamental Design for a Shoe Sole, as shown in the accompanying drawing, forming part of this specification.

In the drawing:

Fig. 1 is a plan view of the shoe sole showing my ornamental design.

Fig. 2 is a section on the line 2—2, Fig. 1.

Fig. 3 is a section on the line 3—3, Fig. 1.

I claim:

The ornamental design for a shoe sole, substantially as shown.

HOWARD E. CHRISFIELD.
